pany, Milwaukee, Wis., a corporation of Wis-
consin

Application April 1, 1931. Serial No. 526,891

20 Claims. (Cl. 103—162)

This invention relates to pumps.

The pump to which the invention applies in particular has its rotor journalled upon a pindle and provided with cylinders which are parallel 5 to the axis thereof, pistons fitted in the cylinders and reciprocated therein by engagement with a thrust member which is inclined to the axis of rotation, and ports and passageways in the pindle through which liquid is delivered to the cylinders 10 and discharged therefrom.

Liquid escapes from between the complementary surfaces of the pindle and cylinder barrel when the pump is in operation, and this volume 15 of escaping liquid, which is generally designated as the slip of the pump, increases as the pressure created by the pump increases.

The volume of liquid escaping from between the pindle and the cylinder barrel at any given 20 pressure varies according to the variation in clearance between the coacting surfaces thereof and variation in this clearance is caused by wear on the coacting surfaces and by inaccurate alinement of the parts due to compounding slight 25 manufacturing errors which are difficult to avoid in the manufacture of the pump.

An object of this invention is to provide a pump 30 of this character in which the pindle is free to adjust itself within the cylinder barrel.

Another object is to compensate for the lateral 35 thrust of the pressure liquid upon the pindle.

Another object is to reduce the slip of the pump to a minimum by automatically maintaining the oil film between the cylinder barrel and the pindle 40 at the minimum thickness at which the parts will run without seizing or binding.

Another object is to maintain the slip of the pump at a substantially constant minimum volume throughout a wide variation in pump pressures.

Another object is to urge the coacting surfaces of the cylinder barrel and the pindle toward each other by a force which is proportional to the pressure created by the pump.

Another object is to urge the coacting surfaces 45 of the cylinder barrel and the pindle toward each other by both a constant force and a force which is proportional to pump pressure.

Another object is to provide a pump which is 50 compact and sturdy.

Another object is to provide a pump of this character which is efficient in operation.

Another object is to provide a pump which is easily and readily assembled and disassembled.

According to the invention in one of its aspects, 55 the pump has its cylinders arranged in a cylinder

barrel having an axial bore, the pindle extends into the bore and is supported in part by the wall thereof, and a flexible connection retains the pindle in position and allows it to seat itself within the bore. 60

According to the invention in another aspect, the pindle and the bore of the cylinder barrel are tapered and the pindle is urged into the bore of the cylinder barrel by a constant force and also urged into the bore of the cylinder barrel 65 and toward the pressure side of the pump by a force which is proportional to pump pressure.

A pump embodying the invention is illustrated in the accompanying drawings in which the views are as follows:

Fig. 1 is a sectional plan view taken on the line 1—1 of Fig. 3.

Fig. 2 is a longitudinal vertical section taken on the line 2—2 of Fig. 3.

Fig. 3 is a transverse vertical section taken on 75 the line 3—3 of Fig. 2.

Fig. 4 is a diagram of the hydraulic circuit.

The pump has its mechanism enclosed within a casing 1 which is closed at its front end by a removable head 2 and at its rear end by a re- 80 movable head 3.

The casing 1 has a rotatable cylinder barrel 4 supported therein by an anti-friction thrust bearing 5 which is carried by the casing 1 and has the rear face of its outer ring in engagement with a flange 6 formed on the casing 1 and the front face of its inner ring in engagement with a flange 7 formed on the cylinder barrel 4. 85

The cylinder barrel 4 is rotated by a driving shaft 8 which has its front end extended through the front head 2 and supported therein by an anti-friction thrust bearing 9. 90

The bearings 5 and 9 rotatably support the cylinder barrel 4 and the shaft 8 and hold the same against axial movement during rotation thereof. 95

The rear end of the shaft 8 is rigidly secured within a bore 10 which is formed axially in the cylinder barrel 4 and has its rear part tapered to receive the tapered front part of a pindle 11. 100

The cylinder barrel 4 has a number of parallel cylinders 12 formed therein around the bore 10 and communicating at the inner or rear ends thereof with the tapered part of the bore 10 through ports 13 which register alternately with a segmental intake port 14 and a segmental discharge port 15 formed in the tapered part of the pindle 11 diametrically opposite each other. 105

The ports 14 and 15 communicate, respectively, with an intake passageway 16 and a discharge 110

passageway 17 extending rearward therefrom through the pintle 11 and then radially outward through a thrust block 18 which is secured to the rear part of the pintle 11 or formed integral therewith.

The thrust block 18 has an intake pipe 19 and a discharge pipe 20 connected thereto and communicating, respectively, with the passageways 16 and 17. Each of these pipes is preferably provided with a loop or bend to permit deflection thereof and thus allow the pintle 11 to seat itself accurately in the tapered part of the bore 10.

The intake pipe 19 may be connected directly to a reservoir 21 containing a supply of liquid, such as oil, or it may be connected thereto through a gear pump 22 which supplies liquid under pressure to the cylinders 12, as shown diagrammatically in Fig. 4.

Each of the cylinders 12 has a piston 23 fitted therein and urged outward or forward by a helical compression spring 24 which is arranged in the cylinder 12 between its inner or rear end and the piston 23.

The outer or front ends of the pistons 23 project into counterbores 25 which are formed in the cylinder barrel 4 concentric to the cylinders 12.

A plunger 26 is fitted in each counterbore 25 and has its rear end in engagement with the piston 23 and its front end protruding beyond the front end of the cylinder barrel 4.

The springs 24 urge the pistons 23 outward or forward and hold the front ends of the plungers 26 against the inner ring of an anti-friction thrust bearing 27 carried by a cam plate 28 which is pivoted at its lower edge upon a pivot 29 secured in the casing 1.

The cam plate 28 is normally inclined to the axis of the pump and is held in adjusted positions by a lever 30 which is pivoted intermediate its ends upon a stationary pivot 31 and has its lower end in engagement with the front of the cam plate 28 at the upper edge thereof and its upper end in engagement with an adjusting screw 32 threaded through the rear wall of the front head 2.

The screw 32 may be advanced or retracted to swing the lever 30 upon its pivot 31 and change the inclination of the cam plate 28 to thereby vary the stroke of the pump.

When the pump is in operation, the cylinder barrel 4 and the shaft 8 are rotated in the direction of the arrows shown in the drawings, the pistons at the right of the vertical center line of Fig. 3 move outward or forward and draw liquid into their cylinders through the intake ports and passageways, and the pistons upon the other side of the center line move inward or rearward and force liquid from their cylinders through the discharge port and passageway into the discharge pipe 20.

The pistons are forced inward by the outer end of the plungers 26 moving along the inclined face of the cam plate 28 and are moved outward by the springs 24 and, if the gear pump 22 is employed, the pistons are moved outward by the pressure of the liquid delivered thereby. The spring 24 may be omitted when liquid is delivered under pressure to the cylinders 12.

Due to the inclination of the cam plate 28, there is a slight relative radial movement between the axis thereof and the axis of the pistons 23 and, if the ends of the pistons abutted the inner ring of the bearing 27, the friction produced by this movement would create lateral thrusts upon the

pistons which would cause undue wear upon the cylinder walls and result in leakage of the pump.

Consequently, the plungers 26 are interposed between the pistons 23 and the thrust bearing 27 to transmit these lateral thrusts to the walls 80 of the counterbores 25.

In order that hydraulic pressure may not be created in the counterbores 25 by liquid seeping from the cylinders 12, each counterbore has a drain hole 33 formed in its side walls through 85 which liquid is discharged into the casing 1.

When the pump is in operation, the pressure created in the cylinders 12 on the pressure side of the pump is transmitted to that part of the film of liquid which is on the pressure side of the pump between the pintle and the cylinder barrel.

The longitudinal component of this force urges the pintle 11 rearward and tends to force it out of the bore 10, and the lateral component of this force urges the pintle toward the intake side of the pump and tends to make it bear more heavily upon that side of the bore 10 than upon the opposite side thereof.

In order to reduce the force exerted upon the 100 pintle 11 by the pressure liquid, the area upon which this liquid may act is reduced by two circumferential grooves 34 and 35, which are formed in the periphery of the pintle on opposite sides of the ports 14 and 15, and by axial grooves 105 36 and 37 which lead, respectively, from the grooves 34 and 35 to the ends of the tapered part of the pintle.

These grooves also assist in maintaining a lubricating film of liquid over the entire area of 110 the complementary surfaces of the pintle and the cylinder barrel.

The liquid collected by the grooves 35 escapes through the grooves 37 into the casing 1, the liquid collected by the grooves 34 escapes through 115 the grooves 36 into the bore 10 and thence through a drain hole 38 into the casing 1, and the liquid collected in the casing 1 is returned to the reservoir 21 through a drain pipe 39.

The pintle 11 is urged into the bore 10 by a 120 helical compression spring 40 arranged between its rear end and an adjusting screw 41 which is threaded through the rear head 3 and held in adjusted positions by a lock nut 42.

The spring 40 exerts a constant force upon 125 the pintle 11 sufficient to hold it to its seat in the bore 10 until the pressure created by the pump has risen above a predetermined minimum.

The pintle 11 is also urged into the bore 10 and toward the pressure side of the pump by a 130 piston 43 which exerts a force thereon proportional to pump pressure.

The piston 43 is fitted in a cylinder 44 which is arranged in the casing 1 at an angle to the axis of the pump and connected to the discharge 135 pipe 20 by a pipe 45 having a loop or bend therein to allow the pintle 11 to move within certain limits.

The outer end of the piston 43 acts upon the thrust block 18 through an arm 46 thereof which 140 is arranged at an angle to the axis of the pump and is preferably provided with a notch 47 which prevents the thrust block and the pintle from revolving, said notch also having a bearing ball 48 arranged therein to receive the thrust of the 145 piston 43.

The ball 48 is held in position by two springs 49 and allows the arm 47 to move without putting an appreciable amount of lateral strain upon the piston 43, and the piston 43 is held in contact 150

at all times with the ball 48 by a light spring 50 which is arranged in the cylinder 44.

When the pump is in operation, the spring 40 initially holds the pintle 11 to its seat so that the outward moving pistons 23 may draw liquid into their cylinders from the intake passageway 16 and the inward moving pistons 23 may expel liquid from their cylinders into the discharge passageway 17.

10 The discharge liquid flows into the discharge pipe 20 and then through the pipe 45 into the cylinder 44 and, when the pump develops pressure in the discharge pipe, the piston 43 is subjected to this pressure and exerts a force proportional to pump pressure upon the pintle 11 through the thrust block 18 and its arm 46.

The cylinder 44 is preferably of such size and arranged at such an angle to the axis of the pump that the lateral component of the force exerted by the piston 43 upon the pintle 11 is somewhat in excess of the lateral component of the force exerted thereon by the pressure liquid, and the axial component of the force exerted by the piston 43 upon the pintle 11 exceeds the axial force exerted thereon by the pressure liquid.

The initial force exerted upon the pintle 11 by the spring 40 is high enough to maintain sufficient surface pressure upon the lubricating film between the pintle and the cylinder barrel to keep the slip of the pump at a negligible minimum at low pressures but, with any given thickness of lubricating film, the slip of a pump would increase as the pump pressure increases were it not for the piston 43 and the cylinder 44.

35 Therefore, the cylinder 44 is so proportioned and arranged that the force exerted by the piston 43 upon the pintle 11 to force it against its seat is greater than the force which tends to urge it away from its seat in order to decrease the clearance between the coating surfaces of the pintle and the cylinder barrel as the pump pressure rises and thereby maintain the slip of the pump at a substantially constant negligible volume throughout its operating range of pressures.

45 The invention herein set forth is susceptible of various modifications without departing from the scope thereof as hereafter claimed.

The invention is hereby claimed as follows:

1. A pump, comprising a casing, a rotatable cylinder barrel journaled in said casing and having an axial bore and cylinders arranged parallel to said bore around the same and provided with ports communicating with said bore, means for rotating said cylinder barrel, pistons arranged in said cylinders, means for reciprocating said pistons as said cylinder barrel rotates, a pintle extending a substantial distance into said bore to be supported thereby and free from said casing to permit it to move laterally and seat itself in said bore and having intake and discharge passageways for the passage of liquid between said cylinders and the outside of said cylinder barrel and intake and discharge ports communicating with said passageways and arranged in radial alinement with said cylinder ports to register therewith successively as said cylinder barrel rotates, and flexible means for holding said pintle in position and allowing it to float substantially free within said bore.

70 2. A pump, comprising a casing, a rotatable cylinder barrel journaled in said casing and having a tapered axial bore and cylinders arranged parallel to the axis of said bore around the same and provided with ports communicating with said bore, means for rotating said cylinder barrel,

tons arranged in said cylinders, means for reciprocating said pistons as said cylinder barrel rotates, a tapered pintle extending a substantial distance into said bore to be supported thereby and free from said casing to permit it to move laterally and seat itself in said bore and having intake and discharge passageways for the passage of liquid between said cylinders and the outside of said cylinder barrel and intake and discharge ports communicating with said passageways and arranged in radial alinement with said cylinder ports to register therewith successively as said cylinder barrel rotates, and flexible means for holding said pintle in position and allowing it to float substantially free within said bore.

80 3. A pump, comprising a casing, a rotatable cylinder barrel journaled in said casing and having a tapered axial bore and cylinders arranged around said bore parallel to the axis thereof and provided with ports communicating with said bore, means for rotating said cylinder barrels, pistons arranged in said cylinders, means for reciprocating said pistons as said cylinder barrel rotates, a tapered pintle extending a substantial distance into said bore to be supported thereby and free from said casing to permit it to move laterally and seat itself in said bore and having intake and discharge passageways for the passage of liquid between said cylinders and the outside of said cylinder barrel and intake and discharge ports communicating with said passageways and arranged in radial alinement with said cylinder ports to register therewith successively as said cylinder barrel rotates, a spring for holding said pintle in position and allowing it to float substantially free within said bore, and flexible pipes connected to said pintle for connecting said pump into a hydraulic circuit.

85 4. A pump, comprising a casing, a rotatable cylinder barrel journaled in said casing and having a tapered axial bore and cylinders arranged around said bore parallel to the axis thereof and provided with ports communicating with said bore, means for rotating said cylinder barrel, pistons arranged in said cylinders, means for reciprocating said pistons as said cylinder barrel rotates, a tapered pintle arranged in said bore and having longitudinal intake and discharge passageways for the passage of liquid between said cylinders and the outside of said cylinder barrel and transverse intake and discharge ports communicating with said passageways and arranged in the plane of said cylinder ports to register therewith successively as said cylinder barrel rotates, flexible means for holding said pintle in position and allowing it to float substantially free within said bore, and means independent of said flexible means for exerting upon said pintle lateral and axial forces counter to the corresponding forces exerted thereon by the pressure liquid.

90 5. A pump, comprising a casing, a rotatable cylinder barrel journaled in said casing and having a tapered axial bore and cylinders arranged around said bore parallel to the axis thereof and provided with ports communicating with said bore, means for rotating said cylinder barrel, pistons arranged in said cylinders, means for reciprocating said pistons as said cylinder barrel rotates, a tapered pintle arranged in said bore and having longitudinal intake and discharge passageways for the passage of liquid between said cylinders and the outside of said cylinder barrel and transverse intake and discharge ports communicating with said passageways and arranged

A pump, comprising a casing, a rotatable cylinder barrel journaled in said casing and having a tapered bore and cylinders arranged around said bore parallel to the axis thereof and provided with ports communicating with said bore, means for rotating said cylinder barrel, pistons arranged in said cylinders, means for reciprocating said pistons as said cylinder barrel rotates, a tapered pintle arranged in said bore and having longitudinal intake and discharge passageways for the passage of liquid between said cylinders and the outside of said cylinder barrel and transverse intake and discharge ports communicating with said passageways and arranged in the plane of said cylinder ports to register therewith successively as said cylinder barrel rotates, a spring for holding said pintle in position and allowing it to float substantially free within said bore, flexible pipes connected to said pintle for connecting said pump into a hydraulic circuit, and hydraulic means independent of said spring for exerting upon said pintle lateral and axial forces proportional to pump pressure and counter to the corresponding forces exerted thereon by the pressure liquid. 17 120
10. A pump, comprising a casing, a rotatable cylinder barrel journaled in said casing and having a tapered axial bore and cylinders arranged around said bore parallel to the axis thereof and provided with ports communicating with said bore, means for rotating said cylinder barrel, pistons arranged in said cylinders, means for reciprocating said pistons as said cylinder barrel rotates, a tapered pintle arranged in said bore and having intake and discharge passageways and intake and discharge ports communicating with said passageways and arranged in the plane of said cylinder ports to register therewith successively as said cylinder barrel rotates, a cylinder carried by said casing and having its axis arranged at an angle to the axis of said pintle, a piston fitted in said cylinder for exerting a force upon said pintle, and means for directing liquid from the pressure side of said pump into said cylinder to advance said piston and cause it to exert upon said pintle a force having lateral and axial components counter to the forces exerted upon said pintle by the pressure liquid. 18 125
11. A pump, comprising a casing, a rotatable cylinder barrel journaled in said casing and having a tapered axial bore and cylinders arranged around said bore parallel to the axis thereof and provided with ports communicating with said bore, means for rotating said cylinder barrel, pistons arranged in said cylinders, means for reciprocating said pistons as said cylinder barrel rotates, a tapered pintle arranged in said bore and having intake and discharge passageways and intake and discharge ports communicating with said passageways and arranged in the plane of said cylinder ports to register therewith successively as said cylinder barrel rotates, a thrust block carried by said pintle, a cylinder carried by said casing and having its axis arranged at an angle to the axis of said pintle, a piston fitted in said cylinder for exerting a force upon said thrust block, and means for directing liquid from the pressure side of said pump into said cylinder to advance said piston and cause it to exert upon said thrust block a force having lateral and axial components counter to the forces exerted upon said thrust block by the pressure liquid. 19 130

- components counter to the forces exerted upon said pintle by the pressure liquid.
12. A pump, comprising a casing, a rotatable cylinder barrel journaled in said casing and having a tapered axial bore and cylinders arranged around said bore parallel to the axis thereof and provided with ports communicating with said bore, means for rotating said cylinder barrel, pistons arranged in said cylinders, means for reciprocating said pistons as said cylinder barrel rotates, a tapered pintle arranged in said bore and having intake and discharge passageways and intake and discharge ports communicating with said passageways and arranged in the plane of said cylinder ports to register therewith successively as said cylinder barrel rotates, a spring urging said pintle into said bore, flexible pipes connected to said pintle for connecting said pump into a hydraulic circuit, a cylinder carried by said casing and having its axis arranged at an angle to the axis of said pintle, a piston fitted in said cylinder for exerting a force upon said pintle, and means for directing liquid from the pressure side of said pump into said cylinder to advance said piston and cause it to exert upon said pintle a force having lateral and axial components counter to the forces exerted upon said pintle by the pressure liquid.
13. A pump, comprising a casing, a rotatable cylinder barrel journaled in said casing and having a tapered axial bore and cylinders arranged around said bore parallel to the axis thereof and provided with ports communicating with said bore, means for rotating said cylinder barrel, pistons arranged in said cylinders, means for reciprocating said pistons as said cylinder barrel rotates, a tapered pintle arranged in said bore and having intake and discharge passageways and intake and discharge ports communicating with said passageways and arranged in the plane of said cylinder ports to register therewith successively as said cylinder barrel rotates, a spring urging said pintle into said bore, flexible pipes connected to said pintle for connecting said pump into a hydraulic circuit, a thrust block carried by said pintle, a cylinder carried by said casing and having its axis arranged at an angle to the axis of said pintle, a piston fitted in said cylinder for exerting a force upon said thrust block, and means for directing liquid from the pressure side of said pump into said cylinder to advance said piston and cause it to exert upon said thrust block a force having lateral and axial components counter to the forces exerted upon said pintle by the pressure liquid.
14. A pump, comprising a casing, a rotatable cylinder barrel journaled in said casing and having a tapered axial bore and cylinders arranged around said bore parallel to the axis thereof and provided with ports communicating with said bore, means for rotating said cylinder barrel, pistons arranged in said cylinders, means for reciprocating said pistons as said cylinder barrel rotates, a tapered pintle arranged in said bore and having intake and discharge passageways and intake and discharge ports communicating with said passageways and arranged in the plane of said cylinder ports to register therewith successively as said cylinder barrel rotates, a thrust block carried by said pintle and having a bearing ball arranged therein, a cylinder carried by said casing and having its axis arranged at an angle to the axis of said pintle, a piston fitted in said cylinder for engaging said bearing ball, and means for directing liquid from the pressure side of said pump into said cylinder to advance said piston and cause it to exert upon said bearing ball a force having lateral and axial components counter to the forces exerted upon said bearing ball by the pressure liquid.
15. A pump, comprising a casing, a rotatable cylinder barrel journaled in said casing and having a tapered axial bore and cylinders arranged around said bore parallel to the axis thereof and provided with ports communicating with said bore, means for rotating said cylinder barrel, pistons arranged in said cylinders, means for reciprocating said pistons as said cylinder barrel rotates, a tapered pintle arranged in said bore and having intake and discharge passageways and intake and discharge ports communicating with said passageways and arranged in the plane of said cylinder ports to register therewith successively as said cylinder barrel rotates, a spring urging said pintle into said bore, flexible pipes connected to said pintle for connecting said pump into a hydraulic circuit, a thrust block carried by said pintle and having a bearing ball arranged therein, a cylinder carried by said casing and having its axis arranged at an angle to the axis of said pintle, a piston fitted in said cylinder for engaging said bearing ball, and means for directing liquid from the pressure side of said pump into said cylinder to advance said piston and cause it to exert upon said bearing ball a force having lateral and axial components counter to the forces exerted upon said bearing ball by the pressure liquid.
16. A pump, comprising a casing, a rotatable cylinder barrel journaled in said casing and having a tapered axial bore and cylinders arranged around said bore parallel to the axis thereof and provided with ports communicating with said bore, a drive shaft journaled in said casing and connected to said cylinder barrel for rotating the same and supporting the front end thereof, pistons arranged in said cylinders, means for reciprocating said pistons as said cylinder barrel rotates, a tapered pintle extending a substantial distance into said bore to be supported thereby and free from said casing to permit it to move laterally and seat itself within said bore and having intake and discharge passageways for the passage of liquid between said cylinders and the outside of said cylinder barrel and intake and discharge ports communicating with said passageways and arranged in radial alignment with said cylinder ports to register therewith successively as said cylinder barrel rotates, and means for holding said pintle in position within said bore and allowing it to float substantially free therein.
17. A pump, comprising a casing, a rotatable cylinder barrel journaled in said casing and having a tapered axial bore and cylinders arranged around said bore parallel to the axis thereof and provided with ports communicating with said bore, means for rotating said cylinder barrel, pistons fitted in said cylinders and urged outward, a swash plate for moving said pistons inward as said cylinder barrel rotates, a tapered pintle extending a substantial distance into said bore to be supported thereby and free from said casing to permit it to move laterally and seat itself within said bore and having intake and discharge passageways for the passage of liquid between said cylinders and the outside of said cylinder barrel and intake and discharge ports communicating with said passageways and arranged in radial alignment with said cylinder ports to reg-

- ister therewith successively as said cylinder barrel rotates, means for holding said pindle in position within said bore and allowing it to float substantially free therein, and flexible means for connecting said pindle into a hydraulic circuit. 5
18. A pump, comprising a casing, a rotatable cylinder barrel journaled in said casing and having a tapered axial bore and cylinders arranged around said bore parallel to the axis thereof and provided with ports communicating with said bore, means for rotating said cylinder barrel, pistons arranged in said cylinders, means for operating said pistons as said cylinder barrel rotates, plungers fitted in said cylinder barrel in engagement with said pistons for transmitting axial movement thereto from said piston operating means and preventing the transmission of lateral forces thereto from said piston operating means, a tapered pindle extending a substantial distance into said bore to be supported thereby and free from said casing to permit it to move laterally and seat itself within said bore and having intake and discharge passageways for the passage of liquid between said cylinders and the outside of said cylinder barrel and intake and discharge ports communicating with said passageways and arranged in radial alinement with said cylinder ports to register therewith successively as said cylinder barrel rotates, means for holding said pindle in position within said bore and allowing it to float substantially free therein, and flexible pipes connected to said pindle for connecting said pump into a hydraulic circuit. 10
19. A pump, comprising a casing, a rotatable cylinder barrel journaled in said casing and having a tapered axial bore and cylinders arranged around said bore parallel to the axis thereof and provided with ports communicating with said bore, a drive shaft journaled in said casing and connected to said cylinder barrel for rotating the same and supporting the front end thereof, pistons arranged in said cylinders and urged outward, a swash plate for moving said pistons inward as said cylinder barrel rotates, a tapered pindle extending a substantial distance into said bore to be supported thereby and free from said casing to permit it to move laterally and seat itself within said bore and having intake and discharge passageways for the passage of liquid between said cylinders and the outside of said cylinder barrel and intake and discharge ports communicating with said passageways and arranged in radial alinement with said cylinder ports to register therewith successively as said cylinder barrel rotates, means for holding said pindle in position within said bore and allowing it to float substantially free therein, and flexible pipes connected to said pindle for connecting said pump into a hydraulic circuit. 15
20. A pump, comprising a casing, a rotatable cylinder barrel journaled in said casing and having a tapered axial bore and cylinders arranged around said bore parallel to the axis thereof and provided with ports communicating with said bore, means for rotating said cylinder barrel, pistons fitted in said cylinders and urged outward, a swash plate for moving said pistons inward as said cylinder barrel rotates, plungers fitted in said cylinder barrel for transmitting axial movement from said swash plate to said pistons and preventing the transmission of lateral forces from said swash plate to said pistons, a tapered pindle extending a substantial distance into said bore to be supported thereby and free from said casing to permit it to move laterally and seat itself within said bore and having intake and discharge passageways for the passage of liquid between said cylinders and the outside of said cylinder barrel and intake and discharge ports communicating with said passageways and arranged in radial alinement with said cylinder ports to register therewith successively as said cylinder barrel rotates, means for holding said pindle in position within said bore and allowing it to float substantially free therein, and flexible pipes connected to said pindle for connecting said pump into a hydraulic circuit. 20
19. A pump, comprising a casing, a rotatable cylinder barrel journaled in said casing and having a tapered axial bore and cylinders arranged around said bore parallel to the axis thereof and provided with ports communicating with said bore, a drive shaft journaled in said casing and connected to said cylinder barrel for rotating the same and supporting the front end thereof, pistons arranged in said cylinders and urged outward, a swash plate for moving said pistons inward as said cylinder barrel rotates, a tapered pindle extending a substantial distance into said bore to be supported thereby and free from said casing to permit it to move laterally and seat itself within said bore and having intake and discharge passageways for the passage of liquid between said cylinders and the outside of said cylinder barrel and intake and discharge ports communicating with said passageways and arranged in radial alinement with said cylinder ports to register therewith successively as said cylinder barrel rotates, means for holding said pindle in position within said bore and allowing it to float substantially free therein, and flexible pipes connected to said pindle for connecting said pump into a hydraulic circuit. 25
19. A pump, comprising a casing, a rotatable cylinder barrel journaled in said casing and having a tapered axial bore and cylinders arranged around said bore parallel to the axis thereof and provided with ports communicating with said bore, a drive shaft journaled in said casing and connected to said cylinder barrel for rotating the same and supporting the front end thereof, pistons arranged in said cylinders and urged outward, a swash plate for moving said pistons inward as said cylinder barrel rotates, a tapered pindle extending a substantial distance into said bore to be supported thereby and free from said casing to permit it to move laterally and seat itself within said bore and having intake and discharge passageways for the passage of liquid between said cylinders and the outside of said cylinder barrel and intake and discharge ports communicating with said passageways and arranged in radial alinement with said cylinder ports to register therewith successively as said cylinder barrel rotates, means for holding said pindle in position within said bore and allowing it to float substantially free therein, and flexible pipes connected to said pindle for connecting said pump into a hydraulic circuit. 30
